U. S. PATENT OFFICE.

No. 63.

1861.

Whole No. 1,428.

Curtain Loops.

EDWARD MAYNARD, OF BROOKLYN, N. Y.,
ASSIGNOR TO GIBBONS L. KELTY, OF NEW YORK CITY.

Letters Patent for a Design, No. 63, dated May 28, 1861.

SPECIFICATION.

TO ALL WHOM IT MAY CONCERN:

Be it known, that I, EDWARD MAYNARD, of Brooklyn, in the county of Kings, State of New York, have invented or produced a new and original design for a Curtain Loop for holding aside window and other curtains; and I do hereby declare that the following is a full description of the said design, reference being had to the accompanying drawing.

My said invention consists of an ornament applied to the curtain loop; said ornament consists of a medallion *a*, around which the cord *b* passes, so that said cord forms an ornamental border or surrounding for the medallion and the medallion itself adds to the beauty of the cord forming the loop by breaking up the continuous line or expanding the cord passing around it, thus forming a new original ornament to the article of manufacture, the curtain loop.

What I claim and desire to secure by Letters Patent, is the new and original design for ornamenting curtain loops set forth—the same consisting of a medallion surrounded by the cord of the loop as shown.

In witness whereof, I have hereunto set my signature this twenty-ninth day of April, 1861.

E. MAYNARD.

Witnesses:

LEMUEL W. SERRELL,
THOS. GEO. HAROLD.
